UNITED STATES PATENT OFFICE.

LOUIS D. BIERACH, OF MILWAUKEE, WISCONSIN.

FIREPROOF WINDOW.

SPECIFICATION forming part of Letters Patent No. 690,392, dated January 7, 1902.

Application filed August 1, 1901. Serial No. 70,443. (No model.)

To all whom it may concern:

Be it known that I, LOUIS D. BIERACH, a citizen of the United States, residing at Milwaukee, county of Milwaukee, and State of Wisconsin, have invented new and useful Improvements in Fireproof Windows, of which the following is a specification.

My invention relates to improvements in fireproof windows for buildings; and it pertains more especially, first, to the peculiar construction of the window-frame, by which the two opposing vertical walls may be removed for the purpose of reaching the sash-balance weights and cords; second, to the construction of the flanges and grooves, by which the sash are held in place and guided when raised and lowered, and, third, to the means employed for forming a tight joint at the upper and lower edges of the sash.

The construction of my improvements is explained by reference to the accompanying drawings, in which—

Figure 1 represents a vertical section of the window sash and frame provided with my improvements. Fig. 2 is a horizontal section drawn on line xx of Fig. 1. Fig. 3 is a horizontal section showing the manner of securing the panes of glass at the center of the window-sash where more than a single light of glass is used.

Like parts are identified by the same reference-letters throughout the several views.

A represents the window-frame, one side only of which is shown. The respective sides 35 A consist of the vertical sheet-metal wall B, which comprises all that part of the frame between the vertical edges C C, including the two hollow angular columns D E and F, the hollow column F serving as a space for the 40 ordinary sash-weights G G.

H is a removable plate, which comprises all that part between the vertical edges I I. The plate H is formed with two inwardly-extending recesses or grooves J J for the reception of brass or other non-corrosive guiding-flanges K K, which flanges K K are respectively formed of a single piece of sheet-brass, which is folded back centrally upon itself from the outer edge L, whereby the outer edge 45 L is caused to present a smooth rounded surface in cross-section, as indicated in Fig. 1, upon which the bearings of the sash N N are

adapted to slide. The grooves M of the sash are likewise provided with a brass or similar non-corrosive bearing-surface or lining O, 55 which is formed by bending a strip of sheet-brass of the required width in U shape, (shown in Fig. 2,) and inserting it in the groove M M, whereby the friction of the guiding-flanges of the sash and frame is reduced to the minimum. 60

Heretofore the guiding-flanges of the sash and frame have usually been formed of one continuous piece with the galvanized iron sash and frame, and such parts as thus constructed are liable to rust and break, and 65 are therefore not durable, especially so owing to the fact that when galvanized iron is bent at such sharp angles as is necessary in forming the beads and grooves the galvanized surface peels off and the metal is soon 70 destroyed by rust.

P represents the window-glass, which is held in place at its vertical sides by the angular flanges Q, bolts R, and nuts S. The nuts S may be soldered to the inner wall of the 75 sash-frame, and thus supported preparatory to inserting the bolts in the flanges, when said bolts are turned down in said nuts, thereby holding said flanges Q in place. The upper and lower edges of the pane of glass P are 80 held in place in the sash by the grooves T and U. The upper groove T is of such height as will permit the glass to be raised therein far enough to engage the lower edge in the lower groove U, when said glass is permitted to 85 drop in said lower groove, where it is held in place, as indicated in Fig. 1.

When desirous to form a close joint at the upper and lower edges of the window-sash, I provide the frame A above and below the respective sash with U-shaped grooves A' A' for the reception of the flanges B' B', which flanges are formed of strips of sheet-brass, which are folded centrally over upon themselves, as indicated in Fig. 1, where they are secured 95 at their respective marginal edges in said grooves A' of the frame, while their rounded or folded edges respectively extend into corresponding grooves C' C', formed in the opposing edges of the respective upper and lower 100 sash.

It is obvious that, if desired, the flanges B' B' may be permanently secured in the sash instead of the frame, when their projecting edges

will be fitted into corresponding grooves formed in the window-frame.

When more than two panes of glass D' are used, their opposing edges are supported 5 against the vertical metallic central piece E', where they are secured in place by the U-shaped plate or bracket F' and bolt G', as indicated in Fig. 3. The object of the bracket F' is to cover up the joint at the edges of the 10 glass and prevent the water from entering therein. The vertical edges of the window-sash are provided with grooves H' for the reception of the ordinary sash-balance cords or chains I'.

15 To give greater strength to the hollow sheet-metal central piece E', as under some circumstances is required, I provide the same with a solid central bar a, which is held in place by the overlapping sheet-metal flap b, as indicated in Fig. 3.

Having thus described my invention, what I claim as new, and desire to secure by Letters Patent, is—

1. In a fireproof window, the combination 25 of a hollow metallic window-frame; separate non-corrosive metallic guide-flanges, rigidly secured to the opposing vertical sides of said frame; and window-sash provided with longitudinal non corrosive guide-bearings (U-shaped in cross-section) for the reception of 30 said guide-flanges, substantially as set forth.

2. In a fireproof window, the combination 35 of a hollow, metallic window-frame; separate, non - corrosive guide - flanges, respectively formed of a single strip of brass folded longitudinally and centrally back upon itself, and secured to the opposing vertical sides of said window-frame; and window-sash provided with longitudinal non-corrosive guide-bear-

ings, formed of a single strip of brass bent U 40 shape in cross-section, for the reception of said guide-flanges, as set forth.

3. In a fireproof window, the combination 45 of a hollow, metallic window-frame A; vertical sides B, which comprise the several parts between the vertical edges C, C, formed integral, all rigidly secured together; removable vertical plate H, comprising the parts between the vertical edges I, I, secured and interlocked together; separate metallic guide-flanges K 50 rigidly secured in said removable plate H of the opposing vertical side walls of the window-frame; and window-sash, the side rails of which are provided with separate metallic guide-bearings O, for the reception of said 55 guide-flanges, substantially as set forth.

4. In a fireproof window, the combination 60 with the respective sides of the window-frame; of separate non-corrosive guide-flanges L, and with the respective side rails of the sash; of the non-corrosive guide-bearings O formed for 65 the reception of said guide-flanges, and with the top and bottom rails of the respective upper and lower sash, and the contiguous bearing-surfaces of the window-frame above and below said upper and lower rails; of the horizontal flanges B', rigidly affixed at their outer edges in the opposing walls of said window-frame, and adapted to engage in corresponding recesses formed in the opposing edges of 70 the upper and lower rails of said sash, as set forth.

In testimony whereof I affix my signature in the presence of two witnesses.

LOUIS D. BIERSACH.
